UNITED STATES PATENT OFFICE.

CALVIN C. HELMAN, OF CLEVELAND, AND CLEMENT E. BEARD, OF COLUMBIANA, OHIO.

BUMPER.

1,290,187.

Specification of Letters Patent.

Patented Jan. 7, 1919.

Application filed November 20, 1917. Serial No. 202,970.

To all whom it may concern:

Be it known that we, CALVIN C. HELMAN and CLEMENT E. BEARD, citizens of the United States, and residents, respectively, 5 of 10021 Somerset avenue, Cleveland, in the county of Cuyahoga and State of Ohio, and Columbiana, in the county of Columbiana and State of Ohio, have invented certain new and useful Improvements in Bumpers, 10 and do hereby declare the following to be a full, clear, and exact description of the invention, such as will enable others skilled in the art to which it appertains to make and use the same.

15 This invention relates to bumpers for motor vehicles, and the primary object of the invention is to provide one which is so constructed that it will absorb and dissipate the force of an impact to prevent the transmission of the latter to the frame of the vehicle, thus eliminating any injury thereto.

20 A further object of the invention is to provide a bumper which is of neat, durable and substantial design, effective in operation and of inexpensive construction.

25 With these and other objects in view as will appear as the description proceeds, the invention comprises the various novel features of construction, combination and arrangement of parts as will be fully described hereinafter and afterward specifically claimed.

Referring to the drawings:

30 Figure 1 represents a plan view of our improved bumper.

Fig. 2 represents a transverse section view through the same, and shown operatively attached to a motor vehicle, and

35 Fig. 3 represents an enlarged detail horizontal sectional view through a portion of the bumper.

Similar characters of reference are used to denote corresponding parts throughout the accompanying drawings and the following description.

40 In order that the construction and operation of the invention may be readily apparent to those skilled in the art to which the invention relates, we have illustrated an 45 approved embodiment thereof in the accompanying drawings, and will now proceed to fully describe the same in connection with said drawings, in which 1 and 2 indicate a pair of spaced parallel channel bars hav-

ing their ends slightly curved in a rearward direction.

These bars, as clearly shown in Fig. 2 are substantially U-shape in cross section, and have a plurality of spaced pairs of quadrilateral toggle links pivotally connected between and within the channel bars 1 and 2 by bolts 3. Each quadrilateral toggle consists of pairs of links 4 and 5 pivotally connected by the bolts 3 and 6. 7 indicates spacing sleeves positioned on the bolts 3 to hold each pair of quadrilateral toggles in spaced relation. The pivotal bolts 6 are each provided with a pair of spaced sleeves 8 to hold the ends of the quadrilateral toggles in spaced relation.

9 indicates tensioned springs that have their terminal ends coiled around the bolts 6 between each pair of spacing sleeves 8, the tension of said springs 9 being such as will normally maintain the bars 1 and 2 in spaced parallel relation.

45 A buffer spring 10 is positioned between the ends of each pair of toggle links and has its terminal ends also coiled around the bolts 6 between the spacing sleeves 8. 80 These springs serve to absorb and dissipate the force of an impact delivered to the bumper.

50 11 indicates a pair of supporting brackets secured to the forward ends of the vehicle frame, each of which embodies a clamping section 12 to clampingly engage the channel bar 1 to support the bumper in operative position.

55 In the use and operation of the bumper above described and when an impact is delivered to the outer bar 2, the latter will yield toward the bar 1, at the same time increasing the tension on the springs 9, which together with the bumper springs positioned 95 between each pair of toggle links will absorb and dissipate the force of the impact. By providing a bumper which will absorb and dissipate all shocks and impacts, liability of injury to the frame of the vehicle is 100 obviated at the same time lessening the dangers incident to collisions. The tensioned springs 9 will cause the outer bar 2 to assume its normal position with respect to the bar 1 immediately after an impact 105 therewith.

From the foregoing description taken in connection with the accompanying draw-

ings, we desire to have it understood that such changes in construction and arrangement of parts may be made when desired as are within the scope of the appended 5 claim.

Having thus described our invention, what we claim as new is:—

A combined bumper and shock absorber for motor vehicles comprising a pair of 10 spaced parallel bars, means for rigidly supporting one of said bars on the front ends of the vehicle frame, pairs of spaced quadrilateral toggle links positioned between and pivotally connected to said bars, tensioned means connected to and across each 15

pair of toggles, and cushioning means positioned between and connected to each pair of toggles, said tensioned and cushioning means coöperating to simultaneously absorb and dissipate the force of impact delivered 20 to said outer bar.

In testimony whereof we have signed our names to this specification in the presence of two subscribing witnesses.

C. C. HELMAN.
CLEMENT E. BEARD.
